SIGNALING SYSTEM

Clyde J. Fitch, Endicott, N. Y., assignor to International Business Machines Corporation, New York, N. Y., a corporation of New York

Application January 10, 1939, Serial No. 250,092

7 Claims. (Cl. 178—2)

This invention relates to signaling systems and more particularly to a system adapted for two way communication.

The instant application constitutes an improvement over the signaling system described in the copending application, Serial No. 756,443, filed December 7, 1934, now Patent 2,153,178, issued April 4, 1939, wherein a plurality of normally non-conductive signaling channels are provided at a transmitting and receiving station; each channel including an electric discharge device, and wherein individual sources of fluctuating voltages are transformed into polyphase voltages which at each station are impressed upon the signaling channels for conditioning the channels periodically and cyclically at mutually exclusive intervals for control purposes. Signal initiating and indicating means are described in detail hereinbelow and are shown to control selectively the signaling channels at the transmitting station to render them conductive upon operation of the signal initiating means for initiating code combinations of control signals which are effective to render the receiving signaling channels conductive in accordance with the receipt of the signals for controlling selectively the signal indicating means. It was mentioned that individual sources of voltages are provided for conditioning the signaling channels and assumed that the said remotely situated sources of voltages are obtained from synchronous distribution systems.

It is known that for certain applications that such synchronous sources of voltages are not available and that therefore, additional provisions must be made for controlling the synchronous conditioning of the said signaling channels. In the instant application, means will be disclosed whereby the transmitting station controls the synchronous conditioning of the signaling channels at both stations.

For this purpose, certain of the available signaling channels are employed for synchronizing purposes, thus, at the transmitting station a predetermined number of the signaling channels are normally maintained non-conductive and disconnected from the transmission medium for signal control purposes as described in the said copending application, and that, for example, a single signaling channel is connected at all times to the transmission medium so that, upon the periodic and cyclic conditioning of the last mentioned channel, periodic synchronizing signals are impressed continuously upon the transmission medium. In this manner, the normally non-con-

ductive channels are selectively rendered conductive in accordance with the operation of the signal initiating means for initiating a periodically timed control signals, and the selected channel for synchronizing control purposes is effective continuously for initiating periodic synchronizing signals. At the receiving station, corresponding signaling channels are provided which normally are non-conductive, and which are conditioned periodically and cyclically in synchronism with the conditioned signaling channels at the transmitting station. Upon receipt of the timed signals, initiated upon operation of the signal initiating means, such signals are properly segregated and effective to render the corresponding signaling channels conductive at the receiving station which, in turn, are effective to control the associated signal indicating means. A corresponding synchronizing signal channel is provided at the receiving station to be responsive to the periodic synchronizing impulses which upon receipt thereof are effective for controlling the conditioning of the signaling channels at this station.

At each of the stations an independent fluctuating supply source is provided in the form of an oscillation generator adapted to produce oscillations of a predetermined frequency. In the instant application the oscillation generators referred to are shown in the form of electronic oscillation generators; it is understood that other forms of generators of fluctuating power supplies may be employed if desired. Provision is made whereby the oscillation generators referred to are controlled and excited by the periodic synchronizing signals. Therefore, it will be seen that the synchronizing channel at the transmitting station is adapted to be conditioned by the electronic oscillation generator thereat so as to be conductive at periodic intervals to initiate synchronizing signals at such intervals and that the synchronizing signals are effective in turn to sustain further generation of the oscillations produced by the electronic oscillation generator thereat. Receipt of the periodic synchronizing signals at the receiving station is effective to excite the oscillation generator provided thereat which in turn is then effective to generate oscillations of a frequency corresponding to that of the oscillations generated at the transmitting station which in turn are then impressed upon the individual signaling channels including the synchronizing channel to condition these channels and control the conductivity thereof. It will

be seen that the synchronizing channel is rendered conductive periodically to sustain further generation of the oscillations at the receiving station. In this manner, it is possible to provide a signaling system which is self-contained and which can be operated in synchronous relationship irrespective of the normal power sources, the features of which are claimed in copending application Serial No. 239,838, filed November 10, 1938.

It will be shown how to arrange the system just described for two way transmission purposes. To this end, a control switching means is provided with a plurality of control circuits associated therewith for selectively connecting the series of signaling channels for initiating or receiving control signals. Utilizing the common signaling channels for both initiating and receiving the signals, obviously simplifies the circuit arrangement and reduces duplication of the control devices to a minimum. For illustrative purposes, since the signaling system disclosed herein is particularly suited for printing telegraph systems, signal initiating and receiving means will be shown embodied in suitable tele-registering devices employing a plurality of permutation units which may be conditioned upon operation of the character keybars for controlling the signaling channels for initiating character code signals or may be controlled so that, upon receipt of the code signals, controlling the selection and operation of the character typebars is effected.

It will also be shown that upon operation of the said switching means for conditioning the system for transmitting or receiving the character signals, the generating means for the fluctuating power supply is also conditioned for conditioning the signaling channels and terminating the synchronizing signals when the system is conditioned for transmitting purposes, and conditioned to be responsive to the synchronizing signals for controlling the conditioning of the signaling channels when the system is conditioned for receiving purposes.

Therefore, an object of the present invention resides in the provision of a signaling system comprising a series of normally non-conductive signaling channels which are conditioned periodically and cyclically for controlling the conductivity of the channels by utilizing a fluctuating power supply therefor, and associated control means whereby the signaling channels are conditioned for either signal transmission or reception purposes.

Another object of the present invention resides in the provision of a tele-registering device which may be conditioned for controlling the said signaling systems for initiating the character code signals or for being controlled by the signaling system in accordance with code signals received thereby.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a sectional view showing the standard mechanism of one preferred type of recording unit.

Fig. 2 is an exploded view showing the normal position of certain of the parts of the power operated units. Several structural features of the

elements are exaggerated to show clearly the relative positions thereof.

Fig. 27 to Fig. 33, inclusive, show the voltage wave shapes impressed on various sections of the control circuits.

Fig. 34 shows graphically the developed phase displaced impulses representing the differential times at which the electric discharge devices at both the transmitting and receiving stations are rendered conductive.

Fig. 35 shows one method of connecting the signaling circuits at each station for two way transmission purposes.

Signal initiating and indicating mechanism

Before describing the signaling system circuit arrangement, the signal initiating means and indicating means will now be described.

For illustrative purposes, the invention is shown as embodying a well known type of recording unit, which may be similar in construction to the Electromatic typewriter, shown and described in detail in U. S. Patent #1,777,055, and hence requires only the following brief description.

Referring to the drawings and particularly to Fig. 1, well known means are provided for actuating the typebars 16 comprising a constantly rotating roller 18, cooperating with a series of individual power units each comprising a cam 11, the engagement of the cams with the roller being controlled selectively by the character key-bars 17.

Any suitable means may be provided to rotate the power roller in the direction indicated by the arrow, which is adapted to cooperate with two rows of cam units arranged in the front and rear of the roller. The cam 11 may be provided to be pivoted on one arm of a bell crank lever 12 which is pivoted in the frame of the recording unit, as indicated generally by reference character 13, the other arm of the said bell crank lever being operatively connected with an arm of bell crank lever 14 by means of link 15. Another arm of the said lever 14 is connected to the typebars 16 in a well known manner, so as to effect operation of the typebars or any other suitable means connected to the bell crank levers upon selective operation of the controlling keybars 17.

The pivoted bell crank lever 12 is operated by the associated cam 11 whenever the latter engages the driven roller; the engagement of the cam with the roller is controlled by means of the associated control keybar 17 in a manner which will now be briefly described.

Referring now to Fig. 2, the cams occupy normally the positions shown in this figure, which represents one of the rear banks of the units. In this position the impeller-arm 18 is urged, by the associated coil spring 19, against one of the impeller-lugs 20, which at the time is in the lower position, and tends to turn the cam 11 in a clockwise direction. This is prevented, however, by the engagement of one of the detents 21 on the cam, with the upper stop lug 22 on the stop lever 23. If, however, the corresponding keybar is operated, the bifurcated lower end (Fig. 1) of extension arm 24 associated with one of the said keybars 17 engages an arm 25 at the upper end of the stop lever 23 which is provided with an offset projection at its end which extends laterally through an opening in the bell crank lever 12. The arm 25 of the stop lever 23 is then swung rearwardly or to the left as viewed in Fig. 1 about the pivot 26 and its lower end forwardly or to the right as viewed in this figure, thus releasing the cam which then turns under the influence of the spring urged impeller-arm 18. In doing so the upper serrated lobe of the cam is brought into engagement with the power roller, which turns in a counterclockwise direction and therefore causes a continued rolling movement of the cam until the high point has been reached and passed. This causes the whole cam unit to swing around the pivot 13 so as to pull down the corresponding link and actuate one of the typebars or any other mechanism with which the cam unit may be connected.

After the high point of the cam is passed, the cam loses contact with the roller, but the said impeller-arm 18 tends to continue the rotation thereof by engaging the second impeller-lug 29 of cam 11 until the second detent 27 engages one of the stop lugs. Since the half rotation of the cam consumes only a small fraction of a second, it is difficult to release the keybar within this short interval, so that it is the lower lug 28 which is first engaged, but upon the release of the keybar and the return of the stop lever 23 to normal position, this lug 28 disengages the detent, whereupon the impeller-arm rotates the cam slightly, and the said detent then engages the upper stop lug 22.

It is obvious then that depression of a keybar releases the revolvably mounted cam to engage and be actuated by the power roller in turn operating the associated bell crank lever and

its attached links to cause the associated mechanism such as the typebars and other operating mechanisms to be operated. It is to be understood that an individual cam unit is provided for each typebar or other functional mechanism associated therewith.

The action of the cam mechanism has been described with respect to one of the rear bank of cam units; in the case of those of the forward bank the operation is analogous, but the directions of movement and the order of operation of the stop lugs is reversed. For example, if the bifurcated arm 24—a is positioned to engage the arm 25—a at the upper end of stop lever 23—a by virtue of operations of the associated keybar, the said arm is positioned rearwardly or to the left as viewed in Fig. 1, and the lower end of the stop lever 23—a is moved forwardly, that is, to the right as viewed in the said figure. This said operation is effective to release the cam, by virtue of positioning the lower stop lug 28—a out of the path of detent 21—a, thus permitting the spring-urged impeller-arm 18—a to rotate the cam slightly in a clockwise direction to effect engagement of the lower lobe of cam 11 and power roller. Upon completion of a half revolution of the cam 11, the second detent 27—a engages first the upper stop lug 22—a while the stop lever 23—a is in an operated position, but upon release of the associated keybar and the return of the said stop lever to normal positions, this lug 22—a disengages the said detent and the impeller-arm rotates the cam slightly so that the said detent then engages the lower stop lug 28—a, as shown in the figure. In this manner the bell crank lever 12—a is rotated about the pivot 13—a to operate the associated typebar or any other mechanism associated therewith. For further structural details of the cam units, reference should be made to the above mentioned patent.

The description just set forth related to a standard typewriting unit and the mechanical connections between the controlling keybars and typebars. The permutation bar units condition the transmission medium in accordance with the selected characters and control the recording of the said characters at the transmitting station, and the permutation bar unit which is controlled by the conditioned medium to select the keybars in accordance with the conditioned medium and thereby record the characters accordingly will now be explained. It is to be noted that the described mechanical linkages between the keybars and typebars are not modified in any manner so that the unit can be conditioned for three different types of operations, namely, as a printing telegraph transmitting printer unit, as a printing telegraph receiving printer unit, and as a standard typewriting or recording unit.

Referring now to Figs. 3 to 11 and 20, the transmitting permutation unit associated with the Electromatic typewriter will now be described.

The bell crank levers 12 are provided with arms 30 depending therefrom and on which are rotatably mounted individual cam rollers 31 which are displaced whenever the associated bell crank levers 12 are actuated by the released cams 11. The cam rollers 31 are positioned so as to be adapted to position or displace control members 32 whenever the said rollers are displaced, for a purpose now to be set forth.

The permutation bar mechanism will now be described and by referring to Fig. 11 is shown to comprise generally a plurality of permutation

bars or rods 33 provided with keys or fingers 34 and a plurality of selector members 32 (see Fig. 8) provided with tabs or studs 35. More specifically, a permutation rod comprises a shaft 36 flat on one side as shown by reference character 37 so that the tapered keys or fingers 34 having correspondingly shaped openings at the untapered section (see Fig. 9) may be fitted on the said shaft, so that the keys are positioned or rotated in accordance with the shaft. Tubular spacings 38 are provided for accurately spacing the various keys on the shaft 36. It is to be noted that the keys are selectively arranged on the shafts so that some of the tapered ends extend or protrude above the shaft and some extend below or depend from the shaft, the purpose of which will be understood as the description progresses (see Figs. 6 to 6—E).

Shafts 36, of which, in the present example, six are shown, are rotatably mounted in the end plates 39 which also support grooved rods 40. This unit just described and generally designated 41 (Fig. 11) is pivotally mounted at 42 to the typewriter frame by members 43 and is adapted to be locked or fixed in an operating position by being secured to the typewriter frame by means of the bolts and nuts shown generally at 44.

It was mentioned that a plurality of selector members 32 are provided and adapted to be engaged by the cam rollers 31 to be positioned thereby. The selectors 32 are shown slidably mounted on the grooved rods 40 and are all identical in structure. A detail of a selector 32 is shown in Fig. 8 and comprises a member provided with similar forked or bifurcated ends 45; at one end thereof extensions 46 are provided and as shown are adapted to be engaged by the cam rollers 31 to be positioned thereby. Each selector is provided with a rectangular opening 47 so as to be able to straddle the permutation bars 33; and also along one section of the selector member equally spaced tabs or studs 35 are fixed thereon, three studs on each side of the member and alternately positioned thereon.

The selectors 32 are slidably mounted on the grooved rods 40 and held in alignment or position by the grooves. Some of the selectors are arranged so that the studded sections of the selectors are above the bars 33 and others are arranged so that the studded sections thereof are below the bars 33; that is, the selectors are positioned so that the studs of some lie in the plane of the keys extending below the bars 33, and so that the studs of some lie in the plane of the keys extending above the bars.

The purpose of the described arrangement is to permit the studs 25 to engage certain of the keys 34 when the selectors 32 are displaced due to the typewriter cam operation to rotate the engaged keys and thereby rotate the shafts associated with the said keys. The particular keys and shafts rotated upon displacement of the selected selectors depends upon the permutation code selected. The reason for alternating the positions of the studs 35 will now be understood, namely, so that proper clearance is provided for the keys 34 attached to the permutation bars, when the keys are displaced through their angle of rotation, so that during said rotation studs on other selectors are not engaged by the associated keys fixed on the rotated shafts.

It is preferred when the selectors described are used in conjunction with the Electromatic typewriter that the studded sections are alternately

arranged to be positioned above and below the permutation bars, respectively, due to the close spacing of the typewriter cam members; therefore, in accordance with this arrangement, it will be seen that the front typewriter cams displace selectors 32 which are arranged so that the studs thereof engage the keys extending below the bars 33 to rotate the said keys and associated shafts in a counterclockwise direction and that the rear typewriter cams displace the selectors 32 which are arranged so that the studs thereof engage the keys extending above the bars 33 to rotate the said keys and associated shafts in a counterclockwise direction. Upon displacement of the associated shafts and selectors, provision is made to return them to the normal inoperative position by means of springs 48 attached to the bars 33 and posts 49 mounted on the end plates 39 and the springs 50 (Figs. 3 and 5) interconnecting the adjacent selectors 32.

Attached to each end plate 39 is a switch unit 51 comprising three individual switches which may be of the single pole, double throw type. The switch arms 52 are pivoted at 53 and are normally in position to engage contacts 54. The arms 52 are provided with insulating heads 55 and are engaged by keys 56 (Fig. 10 (similar to keys 34) depending from the shafts 36 so that normally the switch arms are positioned against the tension of springs 57 which are attached to the switch arms and the housing of the switch unit 51 to engage the contacts 54; however, upon rotation of the bars 33 in a counterclockwise direction the keys 56 also are rotated in a similar direction, thereby permitting the springs 57 to rotate the switch arms 52 in a clockwise direction so that contacts 58 are engaged by said arms. The tensions of springs 48 are greater than the tensions of springs 57, therefore, when the bars 33 are returned to normal position by the associated springs, the keys 56 return the switch arms 52 to the normal position described to engage contacts 54.

Referring now to Fig. 4, one of the front cams 11 is shown in an operated position and let it be assumed due to the depression of a certain keybar. The displacement of the bell crank lever 12—a causes the cam roller 31 on extension arms 30 to displace a selector 32 to the right and thereby engaging and displacing the keys 34 attached to permutation bars 33 Nos. 2, 3, 4 and 5, causing the shafts to be rotated in a counterclockwise direction and releasing the corresponding switch arms 52 to engage the associated contacts 58.

In Fig. 5, one of the rear cams 11 is shown in an operated position due to depression of the keybar corresponding to a different character, to displace a selector 32 to the left engaging and rotating in a counterclockwise direction the keys 34 fixed to the permutation bars 33 Nos. 2, 3, and 4, to release the associated switch arms 52 to engage the contacts 58.

In this manner, combinations of signal conditions may be initiated in accordance with the chosen permutation code and due to the operation of the associated keybars not only are the associated permutation bars displaced by the power operated units but the latter are also effective to operate the corresponding typebars to effect recording of the characters corresponding to the character signal conditions represented by the operated permutation bars. The linkages operating the typebars have not been altered, so that when the machine is not conditioned for

transmitting purposes the operation of the keys causes the typebars to be operated in a normal manner. The means for conditioning the machine will be described hereinafter; however, it is noted that the signal conditioning means or the contacts operated by the permutation bars must be disconnected from the transmission medium because, upon any operation of the typebars and the power operated units the selectors and described permutation bars are always operated, that is, upon operating the machine as a standard typewriter or as a receiver unit the said described unit is operated.

The permutation unit adapted to be controlled by the conditioned transmission medium will now be explained. This said unit is associated with the operable keybars of the machine and is adapted to select and operate the keybars to operate the common power operated units and typebars which are operated when the machine is conditioned for signal transmitting purposes or for standard typewriting purposes.

Referring now to Figs. 12 to 20, the said unit is shown to comprise generally a plurality of round slotted shafts or bars 60, the slots 61 of which are arranged diametrically opposite one another. The said bars are normally maintained inoperative so that the control levers 62, one for each keybar and attached thereto by link 63, are locked in an inoperative position. Gear units 64 (Fig. 14) are provided at each end of the permutation bar device, comprising three sets of gears, one for each shaft or bar 60. The gears 65, 66 and 67 are rotated continuously by drive gears 68 and are connected to the associated bars 60 by individual clutches 69 (Fig. 15) to drive said bars one revolution. The clutches 69 are controlled by magnets 70 which are energized by control signals and in combinations in accordance with the preferred permutation code. During the rotation of the selected bars 60, certain slots 61 disposed thereon are presented under the control levers 62 so that one control lever is selected and permitted to drop in the channel provided by the slots which are in alignment, operating the control lever and its attached keybar lever, thus causing the character to be recorded.

The permutation bars 60, of which six are shown, are supported in the end plates 71 (see Fig. 12) attached to the gear units 64 which are secured to the supporting casting indicated generally at 72. To prevent sagging of the bars, central supporting posts 73 are provided. The control levers 62 are positioned over the permutation bars 60 (Fig. 13), and are pivotally supported at the ends thereof by rod 14 suitably supported by members 75 attached to the supporting casting 72. Individual springs 76 are attached to the levers 62 to urge the levers against the permutation bars 60. The levers 62 at the other ends thereof are linked to the keybar by connecting links 63, and therefore it will be seen that upon depression of a control lever 62 by spring 76 the link 63 will be moved downwardly to lower the attached keybar and causing the associated power operated unit and typebar to be operated. The levers 62 are kept in correct alignment by means of the comb member 77 attached to the said supporting casting.

The entire supporting casting 72 is pivotally secured to members 78 so that the entire permutation bar unit may be rotated about the pivots 79 (Fig. 20) by removing nuts 79a. The pivot line through the pivots 79 is in line with the center

of attachment of links 63 and levers 62 so that the said unit may be hinged downwardly without disturbing the link connections to the keybars.

The permutation bars are slotted in accordance with any desired permutation code and are arranged so that upon rotation of certain of the bars, one control lever 62 is selected and permitted momentarily to be depressed into the slots by spring 76 thereby depressing the attached link 63 and keybar 17. Referring to Fig. 15, the rotation of bars 60 Nos. 2, 4 and 6, will cause the slots of all the bars to be aligned under the particular control lever 62 shown, thereby permitting said lever to be lowered into the slots momentarily to depress the associated link and keybar, causing the corresponding typebar to be operated.

The bars are rotated as follows: The power driven roller 10 of the typewriter is adapted to rotate the shaft 80 by means of the connecting belt 81. Attached to said shaft is a pair of driving gears 68, the gears positioned so as to engage the gears 66 (Fig. 14) in each gear unit 64. The gears 66 are adapted to rotate the gears 65 and 67. Each of the gears 65, 66 and 67 is attached to individual stud shafts 82 (Fig. 15) upon which are mounted ratchet gears 83. Associated with each ratchet gear 83 is a clutch unit 69 which is secured to the permutation bar 60. A clutch unit is provided for each bar. The principle of operation of the sets of clutch units and gear units are identical and consequently only one set need be explained. It will be seen from Fig. 14 that the directions of motions of the clutch gears 65, 66 and 67 are different, and because of this fact the clutches 69 are made right-hand and left-hand to correspond thereto.

A controlling magnet 70 is provided for each clutch 69. Referring to Figs. 12 and 15, the magnet 70 is provided with an armature 84 secured to a clutch stop arm 85. The said arm, while the magnet 70 is deenergized, is adapted to engage the dog lift lever 86 which maintains the dog 87 in the position shown in the figure to prevent engagement of the tooth 88 on the dog and the ratchet gear 83.

The clutch is shown to comprise (see Figs. 16 to 18) a housing member 89 secured to the permutation bar 60. The member 89 is shaped so as to receive the toothed dog 87. A spring post 90 is fixed in the said member 89 and acts as a guide for spring 91. The dog 87 is shaped so as to fit over the said spring and spring post and when mounted in the channel provided in the housing member 89 it is seen that the spring 91 tends to urge or maintain the dog 87 to the right as viewed in Fig. 17. The dog 87 and housing member 89 are recessed so as to receive the dog lift lever 86 which, when inserted in the housing member, is adapted to be rotated slightly or pivoted about one end thereof. The other end of the dog lift lever extends beyond the housing member and is arranged to engage the stop arm 85 whenever magnet 70 is deenergized. Movement of the dog lift lever 86 moves the recessed dog 87 and when blocked by the stop arm 85 as shown in Fig. 15 positions the dog 87 to the extreme left-hand position against the action of spring 91. A spring-pressed stop 92 engages a notch 93 provided in the housing member 89, preventing the bar 60 to be rotated in a clockwise direction as viewed in the figure, thereby locking the clutch unit so long as the magnet remains deenergized.

Upon energization of the magnet, its armature

84 is attracted and positions the stop arm 85 downwardly about the pivot 94 out of engagement with and out of the path of dog lift lever 86. The spring 91 then forces the dog 87 to the right as viewed in Fig. 15 whereby tooth 88 moves into engagement with the constantly rotating ratchet gear 83.

The signal condition impressed upon the magnet 70 lasts momentarily, so that the stop 85 is positioned in the path of the dog lift lever 86 before one revolution of the clutch has been completed. As the clutch is rotated by the gear 83 and completes its revolution, the dog lift lever engages the stop 85, and as the clutch continues its rotation with the lift lever 86 held stationary by the stop 85, the said lift lever is rotated about its end positioned in the housing member 89 to slide the tooth 88 of dog 87 out of engagement with the ratchet gear 83. When the tooth 88 is brought out of engagement with the said ratchet, driving power is removed from the clutch and permutation bar. The spring 91 within the dog 87 normally would have a tendency to rotate the permutation bar in a reverse direction and permit the tooth 84 to again engage the ratchet gear; however, as previously explained the clutch and bar 68 are locked in the inoperative position by means of the stop 92. Due to the relative high speed of operation, when the toothed dog is forced out of engagement with the ratchet by means of the stop 85, the momentum of the rotating permutation bar and clutch is sufficient to rotate the bar and clutch slightly beyond the position where the tooth 88 just becomes disengaged from the ratchet gear; this carry-over is sufficient to permit the spring-pressed stop 92 to engage the notch 93 locking the clutch and bar against reversed rotation and insuring sufficient clearance between the dog tooth and the ratchet so as to prevent chattering.

The remaining permutation bars are rotated in a like manner upon energization of the associated clutch magnets 70. The magnets are energized practically simultaneously so that when a particular combination of signals causes certain of the magnets to be energized, the corresponding permutation bars are permitted to be rotated one revolution, permitting one control lever 62 to drop in the aligned slots on the permutation bars, thereby recording a character on the power operated typewriter accordingly.

The design of the permutation bar unit should be such that the stroke of the lever 62 is about twice as great as necessary to operate the typewriter keybar. In this manner the clutches are permitted a wide margin of operation and provides sufficient tolerance to allow for variations in timing of the different magnets due to variations in time of arrival of the signals. With reference to Fig. 13, it is seen that when the permutation bars 2, 4 and 6 rotate one revolution, the first 90° thereof, the levers 62 are all maintained in a locked position, the next 90° permits the selected lever to be pulled downwardly by spring 76, the next 90° locks up all the levers again and during the last 90° the bars are positioned as shown in the normal position. It is seen, therefore, that upon reception of a signal the bars are rotated, but even in this event all the control levers are maintained in a locked position except the selected one, in this manner making it impossible to depress more than one control lever and its associated keybar at a time.

It should be mentioned that the keybars 17

are each provided with an elongated slot 95 so positioned that the connecting pin 96 secured to link 63 is effective to cause depression of the keybar when the control lever 62 is lowered into the aligned slots in the permutation bars. This said slot also permits the keybars 17 to be depressed manually without disturbing the link 63 and lever 62, to effect operation of the power operated units and corresponding typebars. In 10 the described manner the machine can be conditioned not to be operated by the conditioned transmission medium yet be operated manually as a standard typing unit. The description thus far dealt with the mechanical elements of the machine and their arrangement so that the machine can be operated as a transmitting unit, a receiving unit, and a standard typing unit, the features of which are claimed in copending application Serial No. 175,370, dated November 19, 20 1937 now Patent 2,181,940 issued Dec. 5, 1939. The signaling system will now be described.

General description of signaling system

Referring now to Fig. 21, the signaling system 25 shows and comprises a plurality of signaling channels including electric discharge devices T-1 to T-8 and R-1 to R-8 at the transmitting and receiving stations designated A and B, respectively. The series of electric discharge devices are shown associated with the phase-splitting transforming means generally indicated by the reference characters 110 and 110-a which, for the instant application, are similar in design and shown in detail in Fig. 22. Individual sources 30 of fluctuating power are impressed upon the phase-splitting transforming means which are effective to generate phase displaced voltages which, in turn, are impressed upon the associated electric discharge devices. The said discharge devices at both the transmitting and receiving stations are conditioned for controlling purposes by the fluctuating power supply periodically and cyclically at mutually exclusive intervals. The 35 power supplies referred to are generated by the electronic oscillation generator systems which are indicated generally in the figure by the reference characters 111 and 111-a, designating the electric discharge devices and the associated circuits which are adapted to generate oscillations of a predetermined frequency. The oscillation generator systems at both the transmitting and receiving stations are similar in design; therefore, hereinafter it will be sufficient to explain in detail the circuit arrangement and operation of 40 only one of these systems. The electric discharge devices at the transmitting station are rendered conductive selectively upon operation of the signal initiating means described hereinabove and generally indicated by the reference character 54.

It is to be noted that normally the signal initiating means 54 maintain the electric discharge devices T-1 to T-8 disconnected from the transmitting circuit arrangement whereas the synchronizing channel including the electric discharge device T-8 is at all times connected thereto for impressing continuously thereon the periodic synchronizing impulses. It is also to be noted that the synchronizing channel is effective at all times to impress the initiated periodic synchronizing signals upon the associated oscillation generator generally designated by the reference character 111, in this manner sustaining further generation of the oscillations which

in turn are effective for controlling the conditioning of the signaling channels.

At the receiving station the devices R-1 to R-6 are rendered conductive in accordance with the control signals received for controlling the energization of the signal indicating control means described hereinbefore and indicated generally by the reference character 70. The synchronizing channel at the receiving station including the electric discharge device R-8 is controlled continuously at periodic intervals by the received synchronizing signals for controlling the energization or excitation of the associated oscillation generator generally indicated by the reference character 111-a. The oscillations generated thereby are of the same frequency as the generated oscillations at the transmitting station, and are in synchronism therewith so that, when the said oscillations are impressed upon the signaling channels at the receiving station, these channels are conditioned periodically and cyclically at the same intervals that the corresponding channels of the transmitting station are conditioned. Thus, it will be seen that the initiated periodic synchronizing signals are effective to control the excitation of the oscillation generators at both stations, in this manner maintaining synchronous operation of the oscillation generators and, of course, in turn maintaining synchronous conditioning and operation of the associated signaling channels of the transmitting and receiving stations.

Phase transforming means

Referring now to Fig. 22, the phase transforming means associated with the signaling channels which may be employed at both the transmitting and receiving stations will now be described.

The phase transforming means is shown to comprise two primary windings 114 and 115 and the associated secondary windings 114-a to 114-f and 115-a to 115-f, respectively. In the circuit including the primary winding 114, a condenser 116 is included, and in the circuit including the primary winding 115, an inductance 117 is inserted, and the values of the condenser and inductance are chosen so that the voltages in the said primary windings are ninety degrees out of phase, the voltage across each primary winding being the same. It is to be noted that the turns ratio of some of the individual secondary windings vary so that the voltages across the said windings vary accordingly. For example, the secondary windings associated with the primary winding 114 comprises two windings 114-a and 114-d of voltages E and four windings 114-b, 114-c, 114-e, 114-f of voltages equal to

$$\frac{1}{2}\sqrt{2}E$$

The secondary windings 115-a to 115-f associated with the primary windings 115 are similarly rated and therefore, when connected as shown in the figure, the output voltages of the connected secondary windings are all of equal values. It is evident from the description thus far, and from the circuit arrangement shown in the figure, that four different phases, equally spaced electrically, namely, forty-five degrees apart, are developed. The phase directions vectorially are shown by the arrows for each of the phases in the said figure. It is to be noted that eight secondary outputs are provided and for this reason the output circuits of the secondary wind-

ings are arranged in pairs. Thus, two circuits each are provided upon which the same phases are impressed, such as the circuits indicated by the designations, phase 1 and phase 5, or those designated phase 3 and phase 7. The purpose of this arrangement will be understood as the description progresses.

Channel conductivity controlling means

Referring now to Figs. 24, 25 and 26, the operation of an individual electric discharge device and the associated circuits which may be connected to any one of the secondary output circuits of the said phase transforming means will now be described, and is shown to comprise an electric discharge device T equivalent to a full wave rectifier and triode in one envelope and which is well known in the art, commonly referred to as a "duplex diode triode type." The diode plates 120 are joined to the terminals of any one of the said secondary windings of the phase transforming means, in the example chosen, indicated at 114-a, the center tap of which is connected to the grid control element 122 of the device T, and by means of the resistor 123 is also joined to the cathode element 124-a thereof. It is evident from this description that normally the grid element of the device is at zero bias, since no current is impressed upon resistor 123; therefore, upon closure of the signal initiating means shown as the contacts 112, a momentary current flow is established in the triode plate circuit as follows: from the positive terminal of the battery a to the resistor b, anode and cathode elements of the device T, to the negative terminal of the said battery. This described condition exists in the circuit for only a comparatively short time because the bias of grid 122 remains no longer at zero value, and is not a constant factor but varies in a timed relationship with the frequency of the fluctuating supply source. The said supply source by means of the winding 114-a is impressed upon the full wave rectifier section of the device and the rectified voltage impressed upon resistor 123 immediately drives the grid bias negative with respect to the cathode. The value of the resistor 123 is adjusted so that before the grid bias becomes effective to reduce the plate current to substantially zero value, a pulse is impressed upon the output circuit just traced so that a short signal impulse is impressed upon the output circuit associated with the resistor b. It is understood now that as the signal initiating means 112 is maintained in an operative position, the device T is rendered conductive periodically so that a series of short equally spaced impulses will be continuously impressed upon the said output circuit and that the frequency of the initiating signals is twice the frequency of the fluctuating supply source. Referring to Figs. 27 to 29, the voltage wave forms impressed upon different sections of the circuit are shown; Fig. 27 represents the sinusoidal wave shape of the voltage impulses impressed upon the diode plates 120 of the device; Fig. 28 represents the rectified wave forms impressed on the resistor 123, and the wave form shown in Fig. 29 represents the impulses generated and impressed upon the output circuit of the devices each time the said device is rendered conductive which as described is at those times that the said voltage supply passes through zero value.

Referring now to Fig. 25, the electric discharge device T and the associated circuits are shown

similarly arranged as shown and described in connection with Fig. 24 with the exception of the additional provision of the condenser 124 connected between one of the diode plates 120 of the device and the associated cathode. It is evident now from the description just set forth that the grid element 122 of the device is at zero bias when the fluctuating supply impressed in the secondary winding 114—a passes through zero, due to the fact that no current is passing through the resistor 123. It is at such periods that the device is conditioned to be conductive thereby permitting current to flow in the associated output circuit. The effect of the condenser 124 as shown in Fig. 23 will now be described.

When the polarity is such that current passes from the diode plate 120 connected to the condenser 124 to cathode, this current passes through the resistor 123 and also charges the condenser 124 to the polarity as shown. At the end of this particular half cycle as the current passes through zero, the charge in the condenser maintains the grid of the device negative with respect to the cathode and is of such value as to be sufficient to permit no plate current to flow. The charge in the condenser leaks off through the resistor 123, the value of the capacitor and resistor being such that the time constant of the circuit is adjusted so as to maintain the device non-conductive during the timed interval that the said half cycle of the power supply passes through zero, and during part of the following half cycle until the current passing from the other diode plate 120 to the capacitor and through resistor 123 has reached sufficient amplitude to maintain the device biased so as to be maintained non-conductive. At the end of the second half cycle the charge in condenser 124 has completely leaked off, and as the said half cycle passes through zero the grid bias is zero, thereby permitting the device to be rendered conductive momentarily. Thus, it is seen that during the transition period during the first and second half cycle, the device is continuously rendered non-conductive, and during the transition period between the second and third half cycles, the condenser having received no charge during the second half cycle, or if any charge, is in the opposite phase thereby having no effect upon the bias and thus permitting the device to be conductive as the fluctuating supply voltage passes through zero. The curve shown in Fig. 31 shows the wave shapes of the rectified voltage across the resistor 123 in the circuit arrangement shown in Fig. 25. The effect of the condenser 124 is evident, namely, suppressing the alternate peaks of the rectified waves as shown, and as just explained, the suppressed waves are effective to maintain the bias of the device such as to render the device non-conductive, whereas the unsuppressed waves are effective to render the device conductive. Thus, it is seen that the device is rendered conductive one time for each complete cycle of the fluctuating power supply impressed thereupon, whereas without the condenser the said device would be rendered conductive two times during a complete cycle of a fluctuating power supply.

In Fig. 31, the impulses indicated therein are representative of the periods at which the device shown in Fig. 25 is rendered conductive and the short current impulses flowing in the output circuit of the device at such times, which is seen from the figure occurs at equally spaced

timed intervals. Now assume that the condenser 124 is connected in the diode plate circuit opposite to that shown in Fig. 25, for example, as shown in Fig. 26, between the cathode and the other diode plate 120. With the condenser inserted in the circuit as shown in Fig. 26, it is obvious that the opposite peaks of the rectified wave forms will be suppressed and render the tube non-conductive. In Figs. 32 and 33, the wave forms are shown when the condenser 124 is included in the circuit as it is shown in Fig. 26. It is seen that the opposite peaks of the rectified waves are suppressed to render the device non-conductive at those particular intervals. The impulses represented in Figs. 31 and 33 indicate comparatively the timed intervals during which the device T is rendered conductive depending upon which diode plate circuit has the condenser 124 inserted therein.

It is now understood that by inserting the condensers in the opposite legs of the diode plate circuits and impressing fluctuating supply sources which are in phase, or of the same phase, upon the discharge devices that two different and separate signal generating circuits are obtained for initiating two series of equally spaced impulses, said series of impulses being separate 180° electrically.

Referring now to Fig. 23, the individual electric discharge devices T-1 to T-8 are shown connected to the individual output circuits of the phase transforming means 110 designated phase 1 to phase 8. It is noted that the condensers 124 associated with the devices T-1 to T-4 are connected in one leg of the individual diode plate circuits thereof and for the devices T-5 to T-8 are connected in the opposite legs of the diode plate circuits. It was mentioned that 40 pairs of similar or like phases of the voltage sources are developed, for example, phases 1 and 5 are shown vectorially to be in the same direction. Therefore, by connecting the individual electric discharge devices and the associated circuits, as described, to the individual secondary output circuit of the phase transforming means, for example, to phases 1 and 5 and having the condensers 124 connected in the opposite legs of the diode circuits as shown, 45 it is understood that the devices T-1 and T-5 are rendered conductive at such intervals to initiate series of control impulses diametrically opposite in phase, that is, 180 electrical degrees apart, as shown in Fig. 34.

50 Thus, it will be understood without further detailed description that with the four different phases developed by the phase transforming means and a twin or double set of secondary circuits, and by connecting the electric discharge devices and the associated circuits thereto, and connecting the condensers 124 inversely in the twin secondary circuits, that eight separate signal generating circuits are obtained to generate eight differently timed signal pulses for control 55 purposes, said pulses being spaced or separated 45° electrically.

The signal initiating means 54 are shown connected to the anodes of the devices T-1 to T-7 and the common conductor 125, so that upon 70 operation thereof the associated devices are rendered conductive to initiate the timed signal impulses and effect energization of the following circuit at the various timed intervals: from the positive terminal of the power supply designated C, to the conductor 125, anodes and cath-

odes of the devices T-1 to T-7, conductors 126 and 127, coil 128 to the negative terminal of the said power supply.

It is seen that the anode element of the device T-8 is connected directly to the conductor 125 so that, whenever the said device is conditioned by the voltage source impressed thereon by means of the secondary output circuit designated phase 8, the said device is rendered conductive at periodic intervals continuously thereby permitting current to flow in the following circuits: from the positive terminal of the power supply C, to conductor 125, anode and cathode elements of device T-8, conductor 129, resistor 130, conductor 127 and coil 128 to the negative terminal of the said supply C. In the event that all the signal initiating means 54 are closed at the same time for initiating the control impulses, the arrangement of the pulses as viewed by a cathode ray oscillograph, for example, would be substantially as shown in Fig. 34, of course, all the impulses would be seen on the same axis or plane, whereas in the figure, for the sake of clarity, each of the series of control impulses is shown in separate planes.

Oscillation generator

The oscillation generators shown in Fig. 21 and employed in the transmitting and receiving circuits are similar to the oscillator circuit fully shown and described in detail in the copending application Serial No. 100,070, filed September 10, 1936 now Patent 2,153,179, issued April 4, 1939. Therefore, the following brief description of the oscillation generator circuits employed in the instant application is deemed sufficient. The operation of the oscillation generator circuit employed in the receiving circuit arrangement is identical to the operation of the generator in the transmitting circuit arrangement which will now be described.

The grid element of the oscillator control tube 111 is shown connected to the resistor 131 and the secondary winding of the transformer 132 which, in turn, is connected to a negative potential so that the control tube 111 is normally biased and conditioned so that no plate current is flowing in the output circuit thereof. Connected to the plate of tube 111 is a tuned circuit arrangement comprising capacitance 133 and inductance 134. The primary winding of the transformer 132 is connected in shunt relationship to resistor 130. Assuming, now for the moment that periodic control impulses are impressed upon the resistor 130 and are of such value as to overcome the bias of tube 111, thereby permitting, whenever the pulses are impressed upon the resistor 130, current to flow from the positive terminal of the potential source designated D through the said tuned circuit arrangement to the anode and cathode elements of the tube 111 to the negative terminal of the said source. The current flow established through the tuned circuit causes excitation thereof at a frequency depending upon the LC constants of the oscillatory circuit. The oscillatory circuit just described is shown coupled to any suitable amplifier and filter arrangement generally designated by the reference character 135 by means of the coupling condenser 136 and resistors 137 and 138, so that the oscillations generated by the said tuned circuit are impressed upon the amplifier and filter arrangement through the said coupling condenser and resistors. The coupling means, just referred to, which is inserted between the tuned

circuit and the input of the amplifier arrangement 135 also is suitable as a phase shifting means. Different adjustments of the phase shifting may be effected and varied slightly by means of adjusting the resistor 138 referred to. The generated oscillations are then amplified by any suitable arrangement designated 135 which may also incorporate a suitable filter which is used merely for the purpose of filtering out the higher harmonics in delivering a pure sine wave to the output of the filter. The amplified oscillations are then impressed upon the phase transforming means 110 which as described hereinabove is then effective to transform the voltage input into a multiphase voltage supply source. For further descriptive details of this oscillation circuit, reference may be made to the aforementioned Patent 2,153,179.

Transmitting circuit arrangement

Referring now to Fig. 21, the operation of the signal generating and transmitting circuits will now be understood.

The individual signaling channels including the electric discharge devices T-1 to T-6 are connected to the individual output circuits of the phase transforming means 110, several circuits of which are shown in detail in Fig. 21. The signal initiating means 54 included in the individual signaling channels are connected in common to the conductor 125 and the individual plates of the devices T-1 to T-6. As mentioned hereinabove, the signal initiating means 54 may be operated singly or in different code combinations by the mechanisms described for controlling the conductivity of the individual signaling channels associated therewith. Upon operation of any of the signal initiating means 54, equally spaced timed signals will be initiated. The timing of the out-of-phase control signals, with respect to each other, is controlled by the phase displaced voltages impressed upon the input circuits of the electric discharge devices. The signaling channels just referred to relate to those associated with phases 1 to 6 of the phase transforming means 110. In Fig. 21, phase 7 is not shown to be included in the transmitting and receiving circuits. This phase may be used for other controlling purposes not relevant to the present invention. Phase 8 of the phase transforming means 110 is shown connected to a signaling channel, which will be referred to hereinafter as the synchronizing control channel and is shown to include the electric discharge device T-8, connected directly to the common conductor 125. The cathode element of the device T-8 is connected by means of the conductor 129 to one terminal of the resistor 130. The cathode elements of the devices T-1 to T-6 are connected in common by the conductor 126 to the other terminal of the said resistor 130 and also by means of the conductor 127 is extended to an output circuit comprising the control tube 139 and output transformer 140. The control tube 139 is adapted to be biased so that normally no plate current is flowing in the output circuit thereof including the primary winding of the transformer 140.

Assume now that the control switch 141 is closed and that the signal initiating means 54 remain unoperated for the moment, current flow is immediately established through the synchronizing control channel as follows: from the positive terminal of supply source C, through conductor 125 to the anode and cathode elements of

the device T-8, conductor 128, resistor 130, conductor 127, coil 128 to the negative terminal of the said source. This momentary flow of current is effective to reduce the grid bias impressed upon the control tube 139 so that current flow is now established in the output circuit thereof as follows: from the positive terminal of the potential supply source E, through the tuned circuit arrangement including the primary winding of transformer 140 to the anode and cathode elements of the said tube to the negative terminal of the said supply source, thus impressing upon the transmission medium generally designated 142 associated with the secondary winding of the transformer 140 a control signal which will be identified as the synchronizing control signal. The voltage drop across the resistor 130 is also effective to reduce the grid bias of the tube 111 of the oscillator circuit permitting this tube in turn to be conductive and as described hereinabove excite the associated tuned circuit arrangement comprising the condenser 133 and the inductance 134 to initiate oscillations of a predetermined frequency which are then, in turn, impressed upon the amplifier arrangement 135 and in turn impressed upon the input circuit to the phase transforming means 110. Immediately upon impressing the oscillations upon the phase transforming means, the device T-8 is rendered non-conductive except at those periods when the voltage impressed upon the said device passes through zero and due to the insertion of the condenser 124 in one leg of the diode plate circuit thereof, the device T-8 is rendered conductive only one time for each complete cycle of the voltage supply. Immediately upon building up of the voltage supply source by means of the excited oscillator generator circuit, impulses are generated by the synchronizing channel including the device T-8 at the rate of one impulse for each cycle, which impulses are then impressed upon the resistor 130 for periodically controlling the operation of the oscillator control tube 111 which in turn controls the excitation of the associated tuned circuit thereby sustaining further generation of the oscillations which are impressed upon the phase transforming means and, secondly, for controlling the conductivity of the control tube 139 thereby impressing periodically synchronizing control signals upon the transmission medium 142 associated with the secondary winding of the transformer 140. In this manner, it is seen that the synchronizing channel is rendered conductive periodically for continuously controlling the excitation of the oscillator circuit and for continuously impressing periodically, at intervals, synchronizing impulses upon the transmission medium. The generated oscillations which are impressed upon the phase transforming means 110 are effective to control the conditioning of the signaling channels including the devices T-1 to T-6 for controlling the conductivity of these channels whenever the signaling initiating means 54 associated therewith are operated.

It is seen that upon operation of the signal initiating means 54, the various character signals are impressed upon the common conductor 128 and upon the conductor 127 to control the conductivity of the control tube 139 which, in turn, is effective to impress control signals upon the output transformer 140 and the connected transmission medium 142. The circuits controlled by the control signals initiated by the signaling and synchronizing channels will now be described.

Receiving circuit arrangement

Referring now to Fig 21, the operation of the receiving circuit will be described briefly. The individual receiving signaling channels including the electric discharge devices R-1 to R-6 and the synchronizing channel including the device R-8 are shown connected to the individual output circuits of the phase transforming means 110-a, several circuits of which are shown in detail. The said phase transforming means corresponds exactly to the phase transforming means 110 and is adapted by means of the poly-phase voltages developed thereby to control the conditioning of the connected circuits including the devices R-1 to R-8 in exactly the same manner as the devices T-1 to T-8 are conditioned for controlling the conductivity thereof; therefore, it is deemed unnecessary to repeat this description at this time.

The plates of the triode elements of the devices R-1 to R-8 are connected in common to the conductor 143 and the cathode element of the control tube 144, the grid element of which is shown connected to the secondary windings of the receiving transformer 145 and a suitable source of negative potential so that normally this tube is biased to be non-conductive during the intervals that no signals are impressed upon the transmission medium 142 which is shown connected to the primary winding of the said transformer 145.

The individual electric discharge devices R-1 to R-6 are shown to be associated with the individual condenser units C-1 to C-6 which in turn are adapted to control the grid circuits of the associated tubes A-1 to A-6. The selective controlling of these circuits will be explained later herein; however, it should be mentioned that the tubes A-1 to A-6 are normally biased so that they remain non-conductive and in this manner maintain the signal indicating control means 70 deenergized until such times when the particular control signals are received and impressed upon the receiving circuit arrangement. As mentioned hereinbefore, the signal indicating control means may be controlled singly or in various code combinations.

Now assume that at the transmitting station the switch 141 is closed and the signal initiating means 54 remain unoperated so that the devices T-1 to T-6 remain non-conductive; it is understood that a plurality of periodic synchronizing impulses are initiated by the synchronizing channel including the device T-8 and impressed upon the transmission medium 142.

The synchronizing signals received at the receiving station are then impressed upon the control tube 144 to render this tube conductive whenever the said signals are impressed upon the grid element thereof. It is now seen that for each synchronizing impulse received the tube 144 is rendered conductive momentarily permitting current to flow through the following circuit: from the positive terminal of the potential source F, anode and cathode elements of tube 144, conductor 146, anode and cathode elements of the triode section of the device R-8 (at this moment the grid element thereof is a zero bias, thus permitting the devices to be conductive), conductor 147, resistor 148, conductor 149, coil 150, and conductor 151 to the negative terminal of the said source. Energization of the resistor 148 is effective to overcome the grid bias on the oscillator control tube 111a, due to the voltage drop across the said resistor which is impressed

upon the grid element of the oscillator control tube by means of the transformer 152. The control tube 111a is rendered conductive momentarily to excite the associated tuned circuit arrangement comprising the capacitance 153 and inductance 154. The generated oscillations, the frequency of which is adapted to be the same as the frequency of the oscillations generated at the transmitting station are then impressed upon the filter and amplifying arrangement generally designated 155 by means of the coupling condenser 156 and resistors 157, and in turn are then impressed upon the input circuit of the phase transforming means 110-a. It is understood now that immediately upon impressing the oscillations upon the phase transforming means the device R-8 is conditioned so as to be non-conductive except at those periods when the voltage impressed upon the said device passes through zero and due to the insertion of the condenser 124-a in the one leg of the diode plate circuit thereof, the device R-8 is rendered conductive only one time for each complete cycle of the voltage supply. Immediately upon building up of the voltage supply source by means of the excited oscillator generator circuit, impulses are generated by the synchronizing channel including the device R-8 at the rate of one impulse for each cycle, which impulses are then impressed upon the resistor 148 for periodically controlling the operation of the oscillator control tube 111-a which in turn controls the excitation of the associated tuned circuit thereby sustaining further generation of the oscillations which are impressed upon the phase transforming means. The operation of the synchronizing and oscillator circuits just described is exactly the same as the operation of the synchronizing and oscillator circuits employed at the transmitting station and described in detail hereinabove.

It is evident now that the synchronizing and oscillator circuits at both stations are operated in exact synchronism. The reason for this is obvious, since the periodic synchronizing signals initiated at the transmitting station control the periodic operation of the oscillator circuits at both stations. It also follows that the devices T-3 and R-8 included in the synchronizing channels are rendered conductive at the same intervals, since the voltages impressed upon the individual circuits are of the same phase, or, stated in other words, are in phase. The impulses developed in Fig. 34 for phase 8 represent the periodic intervals at which the devices T-3 and R-8 are rendered conductive. The frequency at which these devices are rendered conductive depends solely upon the predetermined frequency of the oscillations generated by the described oscillator circuits.

It should be mentioned that upon initial conditioning of the receiving circuits, that is, upon conditioning the system with the synchronizing signals, before initiation of the character signals, that as soon as the first synchronizing signal is impressed upon the receiving circuit arrangement not only is the synchronizing channel rendered conductive momentarily but similarly are the other signaling channels associated with phases 1 to 6 and including the devices R-1 to R-6. However, the individual signal receiving channels can be so arranged that the momentary period of conductivity of these channels effects no faulty operation of the associated signal indicating control means. This can be effected by selecting the capacity of elements

C-1 to C-6 to be of such value so that a predetermined number of received impulses are necessary before the individual capacity elements are effective to discharge and overcome the individual grid bias impressed upon the grid control elements of the tubes A-1 to A-6. It is seen that immediately upon receipt of the first synchronizing impulses that the power supply is instantly generated by the oscillator circuit arrangement and impressed upon the phase transforming means so that control of the signal receiving channels is immediately established; and since the synchronizing signals are the only signals being received at this time and since the channel including the device R-8 is the only channel in phase with the incoming synchronizing signals, consequently receipt of these signals is no longer effective to render the remaining signaling channels conductive.

20 In order to describe briefly how the individual signaling channels may be rendered conductive for signaling control purposes, assume that the signal initiating means 54 at the transmitting station associated with the signaling channel 25 including the device T-1 are operated thereby initiating a series of particularly timed impulses which are impressed upon the transmission medium. It is understood that the character signals initiated and generated thereby are impressed upon the transmission medium in addition to the periodically timed synchronizing impulses which are continuously generated by the synchronizing channel including the device T-8. The continuously initiated synchronizing impulses are effective at all times to control the synchronizing channel at the receiver thereby controlling the generation of the power supply thereto which is impressed upon the phase transforming means and which in turn is effective to control the segregation of the timed character signals which are initiated and generated aperiodically upon operation of the different signal initiating means 54. Continuing now with the example, the character signals generated by 45 the signaling channel including the device T-1 are impressed upon the signal receiving means 145 to render the control tube 144 conductive, at these particular intervals, thus permitting current to flow in the following circuit: from the 50 positive terminal of the potential source F, to anode and cathode elements of tube 144, conductor 146, anode and cathode elements of device R-1, condenser C-1 and resistor L-1 to the negative terminal of the said source. Upon 55 energization of the described circuit by the series of character impulses impressed thereon, the condenser C-1 is charged by a predetermined number of the said series of impulses, which charge leaks off through the resistor L-1 impressing a relatively long continuous impulse on the grid of tube A-1, reducing the bias on the grid element thereby rendering the tube conductive and permitting current to flow in the output circuit of tube A-1 including the signal 60 indicating control means 70. It is seen that the said signal indicating control means is energized as long as the signal initiating means 54 associated with the device T-1 is operated. It is understood from the description just set forth that the remaining signaling channels including the devices R-2 to R-6 are not rendered conductive at the time that the character signals are received which are generated by the signal initiating means associated with the first signaling channel including the device T-1.

It is evident now that the conditioning of the remaining signaling channels including the said devices R-2 to R-8 is such that these remaining channels are not adapted to be rendered conductive at the same timed intervals the said character signals, initiated by the device T-1 are received. It is seen that the signaling channel, at the receiving station, associated with the output circuit of phase 1 of the phase transforming means is conditioned so that the conductivity of this channel is controlled in synchronism with the conditioning of the signaling channel associated with the output circuit of phase 1 of the phase transforming means at the transmitting station. Similarly, the signaling channels at the receiver associated with the remaining phases 2 to 8 of the phase transforming means are conditioned in synchronism with the signaling channels at the transmitting station associated with the phases 2 to 8 of the transforming means thereof. Referring to Fig. 34, the timing arrangement of the different controlled circuits is graphically shown, the impulses for each phase representing the times at which the individual channels at both stations associated with each of the phases are conditioned to control the conductivity of each of the channels. It is seen that each channel is conditioned periodically and cyclically and that the conditioning of the corresponding channels occurs at mutually exclusive timed intervals. It is evident then that the individual signaling channels at the receiving station associated with the different phase output circuits are adapted to be responsive solely to the signals initiated by the individual transmitting signaling channels associated with the output circuits of the corresponding phases of the phase transforming means at the transmitting station.

It is seen, therefore, that the periodic and continuous initiation of the timed synchronizing signals are effective to control the energization of the controlling oscillation generators at both the transmitting and receiving stations, which oscillations are effective to control the synchronous conditioning of the signaling channels at both stations, whereby the signaling channel controlling means can be operated singly or in various code combinations for initiating timed character signals which in turn are segregated by the signaling channels at the receiver and upon segregation thereof the said receiving signaling channels are rendered conductive to control the associated indicating control means accordingly.

Two way transmission system

Referring now to Fig. 35, it will be shown how each station may be arranged to utilize the described signaling system for two way transmission purposes. The circuit arrangement shown in the figure is representative of one station which may be conditioned for either transmitting or receiving purposes. The signal initiating means are shown generally by the group of make and break contacts 54 and 58 which as described are adapted to be controlled by the described associated permutation bar means. The signal indicating control means are shown generally by the control magnets 70 which are adapted to control the described permutation bar means. A common signaling channel arrangement is provided including the electric discharge devices TR-1 to TR-8 and the associated phase transforming means 110-b, the operation of which is identical to the signaling channels just described.

5 An oscillation generator system comprising the control device 111-b and the associated circuit is shown conductively associated with the phase transforming means 110-b and the synchronizing control channel including the device TR-8 and is adapted to be controlled and to generate oscillations of a predetermined frequency, similarly as described hereinabove. A common switching means generally designated by the reference character 200 is provided and is adapted to be arranged in different operating positions to change its status for controlling the circuit connections of the signal initiating and indicating control means and the signaling system. The 10 said switching means is provided with a plurality of contacts 201 to 223 which are selectively conditioned when the switching means is positioned for sending or for receiving purposes, respectively. In order to provide additional features 15 in the present system, certain changes have been made in the circuit connections as compared to those described hereinabove, which will be described as the description progresses.

20 Let it be assumed that at one station the arrangement shown in Fig. 35 is conditioned for signal transmitting purposes and that the switching means 200 is positioned so that the contacts 201 to 211 are conditioned to be conductively associated with the control elements of the signaling system, and that the main switches 225 are closed; assume further that upon closure of the main switches that all the tube heater elements are connected thereby to suitable potential sources thereby conditioning them for operation.

25 30 It is to be noted that a time delay device 226 is provided and by means of a suitable resistor 227 in the associated heater element circuit is adapted to delay the conductivity period of the device 228 as compared with the other electric discharge devices employed. When the device 226 is rendered conductive, the coil of relay 228 in the plate circuit is energized to open the associated contacts 229 and thereby remove the shunt circuit across the signaling line. It should be 35 mentioned that the plate current of device 228 also flows through resistor 230 associated with the control device 111-b raising the potential drop thereacross and thus the bias impressed on the said control device, the purpose of which will be understood shortly.

40 45 50 The oscillation generator and synchronizing signal generator circuit arrangements will be described first and assuming that the main switches have just been operated and that all the tube devices are conditioned for operation excepting the time delay device 226, the following circuit is established immediately: from the positive tap 231 of the potential source G, conductor 232, contacts 207, conductor 233 connected in common to the anodes of devices TR-1 to TR-8 (all the said devices at this instant are at zero bias, and the cathode circuits for devices TR-1 to TR-8 are open for the moment by means of the permutation switches) anode and cathode of device TR-8, resistor 130-a, winding 128-a and conductor 234 to the negative terminal of the potential source. In the present circuit arrangement the control device 111-b normally is biased for class A operation by means of the self biasing resistor 230 so that the slight variations existing in the flow of current through the described circuit and which are impressed upon the grid of device 111-b by means of the transformer 132-a are sufficient to cause suitable variations in the plate circuit of the device

to energize the tuned circuit comprising condenser 133-a and winding 134-a, the oscillations of which are amplified by device 235 and amplifier 135-a and fed to the phase transforming means 110-b, where the circuit of phase 8, being coupled to the grid of device TR-8 modulates the plate current of the device TR-8 which further affects the variations across resistor 130a; this action being repeated, the oscillations are quickly built up, the frequency of 10 which is determined by the said tuned circuit.

Immediately upon building up of the supply source by means of the oscillation generator, the device TR-8 is controlled thereby in a manner now understood, so that this device is conductive 15 only one time for each cycle of the voltage supply for generating the periodic synchronizing impulses which are impressed upon resistor 130-a and the control device 111-b and associated circuits to sustain further generation of the oscillations. Assume now that the time delay device 226 is sufficiently conditioned and rendered conductive, this current flows through resistor 230, as mentioned hereinabove, and causes the device 20 111-b now to be biased below the cut-off point, so that the device remains non-conductive during the intervals the synchronizing impulses are not impressed thereupon. In this manner an exceptionally constant frequency generator is obtained. Although the circuit just described will 30 not start oscillating normally if the device 111-b is biased below cut-off, it will start if given a shock, for example, by operating the send-receive switch. In other words, once all the devices are heated sufficiently and in operating condition, 35 operating the send-receive switch from the receiving to the sending position will give the circuit a sufficient shock to start the generation of the oscillations.

The impulses impressed upon the winding 40 128-a are also impressed, by means of the circuit comprising conductor 236 and contacts 211, upon the output control device 139a whose output circuit is connected to the line transformer 45 140-a through the contacts 210 and 209. The winding 128-a is shunted by the condenser 237 which represents the distributed capacity of the associated circuit, and may be adjusted for any desired predetermined frequency. When the impulses are impressed upon the described circuit, 50 they tend to oscillate said circuit, comprising the winding 128-a and condenser 237, at the desired predetermined frequency, but the circuit is highly damped by the resistor 238 so that only one cycle is generated. The single cycle signals are 55 then impressed upon the grid element of the control device 139-a, the cathode element of which is grounded by means of contacts 208 and conductor 239. It is to be noted, that for transmitting purposes, the grid element of the device 60 139-a is biased by means of the tap 240-a of the voltage supply H, so that the device 139-a is conditioned for class A operation.

The sine wave synchronizing impulses impressed 65 upon the grid of the device 139-a appear amplified in the anode circuit thereof with square peaks since the current limiting resistor 240 cuts off the upper parts of the waves while the negative half cycles of the pulses drive the device below cut-off, cutting off the lower parts of the 70 waves. The said anode circuit of device 139-a is as follows—from the positive terminal of supply source G to conductor 241, contacts 209, primary winding of transformer 140-a, contacts 210, anode and cathode elements of device 75

139-a, conductor 238, and contacts 208 to ground; the signals are then impressed upon the line by means of the secondary winding of transformer 140-a.

The character signals are initiated by closing the various cathode circuits of the devices TR-1 to TR-8 by means of the permutation switches. It is to be noted that the permutation control switches are connected differently for the two way transmission system, for example, if it is desired to transmit a character signal comprising impulses of phases 1 and 2, the switches corresponding to these phases are not operated, whereas the switches for the other phases are operated, thus the contacts 54 for phases 3 to 6 inclusive are closed and contacts 58 for these phases opened, thereby permitting current to flow from the cathodes of devices TR-1 and TR-2, to contacts 201 and 202 respectively, contacts 58, common conductor 245 to the conductor 238 by means of the contacts 54 (now closed) to the winding 128-a, thus impressing the signals upon the control device 139-a, output transformer 140-a and the associated line, in the same manner as the synchronizing signals are impressed thereupon and just described.

Thus, it is seen that by positioning the switch 200 so that the contacts 201 to 211 are conductively connected to the described control elements, that the signaling system is conditioned for transmitting purposes. It is now understood that upon operation of the switching means in a sending position, the oscillation generator is immediately conditioned to be effective to generate a suitable voltage supply which is impressed upon the phase transforming means and synchronizing control channel for initiating automatically a series of periodic synchronizing impulses which are then impressed upon the line associated with the switching device. The system is now conditioned so that upon operation of the character signal initiating means various code combinations of the signal impulses are initiated and impressed upon the said line. Now it will be shown how the described control elements may be conditioned upon operation of the switching means to utilize the synchronizing and character signals for controlling the operation of the signal indicating means.

Assume now that the switching means 200 is positioned so that the contacts 218 to 223 are connected to the control elements and that the main switches 225 are closed, and furthermore that the electric discharge devices are conditioned for operation, and that synchronizing signals from the transmitter are impressed upon the line and associated transformer 140-a. The terminals of one winding of the said transformer are connected to the contacts 220 and 221 and a volume control device 250, the center tap of which is connected to contacts 223 and the grid element of control device 139-a. One terminal of the volume control device is connected to the resistor 251 and condenser 252 to provide a fixed bias for the device 139-a by means of the constant voltage impressed upon condenser 252 so that the device is now biased so as to be non-conductive during the intervals that signals are not impressed thereupon. Now it is seen that, when the signals are impressed upon the grid element of device 139-a, this device is rendered conductive permitting current to flow in the circuit which can be traced as follows: from the tap 231 of supply source G, to conductor 232, contacts 222, anode and cathode elements of de-

vice 139-a, conductor 239, contacts 218, conductor 233 to the anodes of devices TR-1 to TR-8 (since at this stage of the operation of the system no voltage supply is impressed upon the phase transforming means, the biases of devices TR-1 to TR-8 are zero, so that current from the anode elements can be traced through all of these devices and eventually back to the negative terminal of the supply source, but only the current flow through device TR-8 is effective for the present, the current flow through the others at this time serves no useful function and causes no undesired operations; therefore, the circuit associated with device TR-8 only will be traced now) cathode element of device TR-8, resistor 130-a, winding 128-a, conductor 234 to the negative terminal of the said supply source.

The voltage drop across the resistor 130-a is impressed upon the grid element of control device 111-b by means of the transformer 132-a, thus rendering the said device conductive at those intervals when the signals are impressed upon the resistor 130-a. The control device 111-b is biased so as to be normally non-conductive as explained previously. Current now flows momentarily through the following circuit from the tap 255 of supply source H to the tuned circuit comprising capacitance 133-a and inductance 134-a, anode and cathode elements of device 111-b through the biasing resistor 230 to ground which is negative with respect to the tap 255 of the supply source H. Since the synchronizing impulses are impressed upon the control device 111-b at a certain predetermined frequency, the associated tuned circuit comprising condenser 133-a and inductance 134-a is energized at the said frequency to generate oscillations at this same frequency which are then amplified by device 235 and amplifier 135-a and then impressed upon the phase transforming means 110-b.

It has been explained hereinabove that upon generation of the power supply by the oscillation generator and impressions thereof upon the phase transforming means that control of the signal receiving channels is immediately established; and since the synchronizing signals are the only signals being received at this time and since the channel including the devices TR-8 is the only channel in phase with the incoming synchronizing signals consequently this channel is the only one rendered conductive, all the remaining channels being out of phase and therefore non-conductive.

When the character signals arrive, they also are impressed upon the grid element of the device 139-a, the impulses being repeated in the anode circuit thereof and impressed upon the common conductor 233 and anodes of the devices TR-1 to TR-8. It is understood that the character impulses can only be effective to render those devices TR-1 to TR-6 conductive which are conditioned in synchronism with the incoming character signals. A single circuit will be traced by assuming that a character signal comprising phase 1 is being received. Since device TR-1 is the only one conditioned in synchronism with the said signals, it is the only one rendered conductive by the signals permitting current to flow in the following circuit: from tap 231 of supply source G, conductor 232, contacts 222, anode and cathode elements of device 139-a, conductor 239, contacts 218, conductor 233, anode and cathode elements of device TR-1, contacts 212, condenser C-1 shunted by resistor L-1 to the negative

terminal of the supply source. The signals charge the condenser C-1, which charge leaks off through resistor L-1 impressing a relatively long continuous impulse on the grid element of device 5 A-1 which is biased so as to be normally non-conductive. The impulses charging condenser C-1 are effective to render the device A-1 conductive permitting current to flow in the following circuit: from the positive terminal of supply source G to conductor 241, contacts 219, conductors 260 and 261, magnet 70, anode and cathode elements of device A-1 to ground, energizing the said magnet thus operating the permutation clutch unit. The signals for the other phases can be traced similarly for energizing the corresponding permutation clutch unit magnets. Thus, it has been shown how the various control devices of the signaling system may be conditioned by the common switching means for reception of the synchronizing and character signals; and that the synchronizing signals are effective to excite the oscillation generator at periodic intervals for generation of the voltage supply which, when impressed upon the phase transforming means, is effective to condition the signaling channels so as to control the conductivity thereof, so that upon receipt of the character signals proper segregation thereof is effected for controlling the signal indicating mechanism in accordance with the received signals.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. A signaling system comprising a plurality of stations, a plurality of normally non-conductive signal channels at each station and means including a fluctuating power generating means for conditioning the signaling channels thereat periodically and cyclically at mutually exclusive intervals for controlling the conductivity thereof, means at each station for initiating or responding to aperiodic control signals, and manually controlled means at each station, in one status, for conditioning its signaling channels for initiating the control signals and preventing response to aperiodic control signals thereat, and in another status, for conditioning said channels for responding to control signals and preventing initiation of aperiodic control signals thereat.

2. A signaling system comprising a plurality of stations, a plurality of normally non-conductive signaling channels at each station, means including oscillation producing means for conditioning the signaling channels thereat periodically and cyclically at mutually exclusive intervals for controlling the conductivity thereof; means at each station including its signaling channels and associated conductivity controlling means for rendering said channels conductive for initiating or responding to character and synchronizing signals, means at each station controlled by synchronizing signals for controlling the oscillation producing means to sustain further operation thereof to condition the associated channels, and means at each station, in one status, for conditioning its signaling channels for initiating the character and synchronizing signals and preventing re-

sponse to character control signals thereat and, in another status, for conditioning said same signaling channels for responding to the character and synchronizing signals and preventing initiation of control signals thereat.

3. A signaling system comprising a plurality of stations, a plurality of normally non-conductive signaling channels at each station and means including a fluctuating power generating means for conditioning the signaling channels thereat periodically and cyclically at mutually exclusive intervals for controlling the conductivity thereof, means including tele-indicating means at each station and including its signaling channels for initiating or responding to aperiodic control signals, and means at each station, in one status, for conditioning its signaling channels for initiating the control signals and preventing response to aperiodic control signals thereat and, in another status, for conditioning said same signaling channels and tele-indicating means for responding to the control signals and preventing initiation of control signals thereat.

4. A signaling system comprising a plurality of stations, each station provided with a plurality of normally non-conductive signaling channels and means thereat comprising an oscillation generating system for conditioning the signaling channels periodically and cyclically at mutually exclusive intervals for controlling the conductivity thereof, means at each station including its associated conductivity controlling means for rendering its channels conductive for initiating or responding to character and synchronizing signals, means controlled by synchronizing signals for controlling the oscillation generating systems for sustaining further operation thereof for conditioning the associated channels, and means at each station, in one status, for conditioning its signaling channels and associated oscillation generating system for initiating the character and synchronizing signals and preventing response to character signals thereat, and, in another status, for conditioning said same signaling channels and associated oscillation generating system for responding to the character and synchronizing signals and preventing initiation of character signals thereat.

5. In a system of the character described, a station adapted for both transmitting and receiving and comprising a plurality of normally non-conductive signaling channels, means for conditioning these channels periodically and cyclically at mutually exclusive intervals for controlling the conductivity thereof, transmitting means including said channels and means for rendering said channels conductive aperiodically and selectively to initiate aperiodic control signals, receiving means including said channels and means responsive to control signals including

means for rendering certain of said conditioning channels conductive in accordance with the signals, and means, in one status, for conditioning said transmitting means for initiating signals and rendering said receiving means inoperative to receive and, in another status, conditioning said receiving means for responding to control signals and rendering said transmitting means inoperative to initiate aperiodic signals.

6. In a system of the character described, a station adapted for transmitting and receiving and including a plurality of normally non-conductive signaling channels, means for conditioning the channels periodically and cyclically for controlling the conductivity thereof, transmission means for rendering certain of the channels conductive aperiodically and including means for initiating aperiodic control signals when the said channels are rendered conductive, means for rendering another of said channels conductive continuously at periodic intervals for initiating synchronizing signals, receiving means including said control channels and means responsive to aperiodic control signals, and means, in one status, for conditioning said signaling channels for initiating the control signals and rendering said receiving means inoperative to receive and, in another status, for conditioning, the same channels and said responsive means, for receiving and rendering said transmission means inoperative to initiate aperiodic signals.

7. In a system of the character described, a station adapted for transmitting and receiving, and comprising a series of signaling channels each including a normally non-conductive electric discharge device, means for generating oscillations for conditioning each of said devices periodically and cyclically at mutually exclusive intervals to control the conductivity of the associated electric discharge device, means, cooperating with said channels for rendering the associated devices conductive, for initiating both aperiodic and periodic control signals, means responsive to periodic signals for controlling said oscillation generating means to sustain further operation thereof, for conditioning the associated channels and devices, means including said channels and responsive to aperiodic signals for segregating the signals including means for rendering the corresponding devices conductive for control purposes, and means, in one status, for conditioning said discharge devices for initiating control signals and rendering said aperiodic signal responsive means inoperative and, in another status, for conditioning the same devices and said aperiodic signal responsive means for receiving and rendering said initiating means inoperative to produce aperiodic signals.
